Ex

No. 11,307

July 29, 1879

UNITED STATES PATENT OFFICE

SIGMUND FEUST AND JULIUS NEUMANN, OF NEW YORK, N. Y.

DESIGN FOR BUREAUS.

Specification forming part of Design No. **11,307**, dated July 29, 1879; application filed June 2, 1879.
[Term of patent 3½ years.]

To all whom it may concern:

Be it known that we, SIGMUND FEUST and JULIUS NEUMANN, of the city, county, and State of New York, have invented a new and original Design for Tops for Articles of Furniture, of which the following is a full, clear, and exact description, reference being had to the accompanying photographic illustration, making part of this specification.

The object of this design is to furnish an ornamental top for bedsteads, dressers, washstands, and other articles of furniture; and it consists of a cornice supported on side pillars, and surmounted by a railing and an ornamental center-piece. The cornice and top strip of the gallery are extended beyond the pillars and supported by symmetrical brackets.

Referring to the illustration, A A represent the supporting-pillars, which rise from projecting pedestals *a a*. The pillars A A support a cornice, B, above which the railing C is arranged. The capitals *b* of the pillars are extended to the height of the railing C, and surmounted by vase or goblet shaped terminals *d*. Above the railing rises an ornamental head-piece, D, which consists of a panel, intermediate cornice, and triangular crown-piece. Symmetrical scroll-shaped ornaments *e* extend from the sides of the panel of the head-piece

D, along the top strip, *f*, of the railing, to the capitals *d*. The cornice, as well as the top strip, *f*, of the railing C, is extended at both sides beyond the pillars, and supported, respectively, by projecting symmetrical brackets E and by inverted fan-shaped supports *f'*, that rise from the extensions of the cornice. The railing imparts a light and pleasing appearance to the tops of furniture, and relieves the otherwise heavy character of same.

What we claim as new, and desire to secure by Letters Patent, is—

The design for a top of articles of furniture, consisting of side pillars, cornice, railing, and surmounting head-piece, the pillar-capitals being extended to the height of the railing, and the cornice and top strip of railing beyond the capitals, and supported by symmetrical brackets and inverted fan-shaped ornaments, as shown and described.

In testimony that we claim the foregoing as our invention we have signed it this 29th day of May, 1879.

SIGMUND FEUST.
JULIUS NEUMANN.
